MODEL PASSENGER RAILWAY CAR TRUCK

Willis G. Stewart, Portsmouth, R. I., assignor to
Midgale Models Inc., Portsmouth, R. I., a corporation of Rhode Island

Application September 26, 1946, Serial No. 699,400

3 Claims. (Cl. 105—182)

1

This invention relates to improvements in scale model railway passenger car truck assemblies.

The object of my invention is to provide a model railway car truck that reproduces with a high degree of faithfulness its prototype and, at the same time, a truck as described, that may be assembled by its user. Another feature of my invention is its ability to be used on double polarized track without fear of short circuiting the system.

A further feature of my invention is its shock absorbing system that allows the truck to be run at relatively high speeds over switches, crossings and rough track without fear of derailment.

Other objects and features of my invention will make themselves apparent during the course of the following description when taken with the accompanying drawings in which:

Figure 1 is a side elevation of the assembled truck;

Fig. 2 is a top plan view of the assembled truck;

Fig. 3 is a cross-sectional view of the coil spring and means for positioning thereof taken at line 3—3 in Fig. 1;

Fig. 3A is a cross-sectional view of another method of positioning the coil spring at line 3—3 in Fig. 1;

Fig. 4 is a cross-sectional view taken at line 4—4 in Fig. 1;

Fig. 5 is a cross-sectional view taken at line 5—5 in Fig. 2; and

Fig. 6 is a cross-sectional view taken at line 6—6 in Fig. 2.

Similar parts in similar figures have been identically numbered.

In the drawings, 1 indicates the bolster member which is manufactured from a dielectric material such as plastic. As shown in Fig. 5, the bolster member 1 has an aperture 2 for the insertion upwardly of a king pin (not shown) to attach the truck to the car. The side frame assemblies are attached to the bolster 1 by rivets 3 passing downwardly through the bolster and a shank extension 4 of the inner side frame member 5. This shank extension 4 is cast integrally with the inner side frame member 5. A simulated leaf spring 6 is also cast integrally with the inner side frame member 5.

The wheel and axle assembly, best illustrated in Fig. 4, comprises an axle 7 manufactured from a dielectric material such as plastic having wheels 8 and spindles 9.

The side frame assembly is made up of the inner side frame member 5 and the equalizer 10. The inner side frame member 5 has vertically elongated apertures 11 as shown in Fig. 6, while the

2

equalizer 10 has normally rounded apertures 12. A journal box 13 passes through the equalizer aperture 12, the inner side frame elongated aperture 11, a washer 14 and contains the axle spindle 9. The journal box 13, after the assembly of the side frame and equalizer to the wheel and axle assembly and bolster, is flared at point 15 as shown in Fig. 4. This flaring retains the washer 14, the inner side frame member 5, the equalizer 10 and the journal in lateral sliding attachment.

Coiled springs 16 are positioned between the bars 17 of the inner side frame member 5 and the bar 18 of the equalizer 10 on studs 19 as shown in Fig. 3. These studs are cast integrally with the members 5 and 10. Fig. 3A shows another method of attaching studs to the bars 17 and 18 of the members 5 and 10 by means of rivets 20 which pass through the bar 18.

These assemblies are put up in kits with all the necessary parts to be assembled by the user. In assembly, the user will first assemble the equalizer 10 and inner side frame member 5 by inserting the journal box 13 through the round hole 12 in the outer side frame 10 and the elongated hole 11 in the inner side frame 5. The washer 14 is then placed over the journal box 13 as shown in Fig. 4 and after the user has made sure that the inner members are capable of vertical sliding movement, the washer is permanently positioned on the journal box 13 by flaring out the journal box 13 at point 15. The coiled springs 16 can now be inserted between the members 5 and 10.

The slotted bolster 1 is then placed over the attaching lug 4 of the inner side frame 5 and the rivets 3 are inserted through the bolster 1 and the lug 4 after the user has drilled the necessary pin holes in the lug 4. The escutcheon pins 3 are riveted in place. The riveting is only done on one side of the truck until the wheel and axle assemblies have been placed in position, after which the opposite side frame assembly is positioned and the riveting at the other end of the bolster is done.

It will be seen that the springs continuously urge the inner and outer side frame members apart in a vertical direction. The equalizer 10 can so move because the elongated holes 11 in the inner frame 5 allow the journal bearing 13 containing the axle 7 to move vertically within the aperture thus absorbing the shock transmitted by the wheels as they strike an intersection or any rough section of track. In addition, the axles and bolster both being made of a dielectric material such as plastic, prevent a short circuit when employed on double polarized track.

This ingenious method of assembly gives full play to the model railway enthusiast's desire for realism as well as his enthusiasm for actually assembling the truck.

While the preferred embodiment of my invention has been described herein, it is to be understood that variations in assembly and parts within the scope of the claims may be employed. There is no intention of limitation to the exact details shown and described.

I claim:

1. A railway truck for scale model passenger cars having in combination a wheel and axle assembly, the axle of said assembly being constructed of a dielectric material, an inner frame having attached integrally thereto a simulated leaf spring and projecting rearwardly from said simulated leaf spring a shank for insertion in a prepared recess in a bolster member, a bolster member having said recess and drilled vertically to receive a king pin, said bolster member being constructed of a dielectric material, said inner frame having two pedestals with a bar extending therebetween and two stud projections on the under side of the bar, said inner frame having vertically elongated apertures in said pedestals to allow free vertical movement of the wheel and axle assembly, an equalizer comprising a bar having two stud projections on the topside thereof positioned opposite to the stud projections on the inner frame, said opposite stud projections in each instance receiving and retaining in position two coil springs, a pair of journal boxes, said equalizer having ends each having an aperture for passage of one of said journal boxes, said wheel and axle assembly including an axle stud projection and said journal boxes each having an axle hole for reception of the axle stud projection, each journal box having a flange at its outer extremity, a washer, for each journal box, each journal box being turned down to receive said washer, said journal boxes being mounted through said inner frame and equalizer apertures, whereby said inner and outer frames are held rigid laterally between said flange and said washer, and said wheel and axle assembly and equalizer being allowed to move vertically in said inner frame elongated apertures, said coiled springs urging apart vertically said inner frame and said equalizer.

2. A railway car truck assembly comprising an outer frame having holes at its ends, an inner frame having holes elongated transversely to the frame, wheel axle bearings for fitting in said holes in the ends of the outer frame and sufficiently long to project through said elongated holes in said inner frame when the two frames are associated together with their holes in registry, and means for application to the ends of said bearings for interfastening said inner and outer frames against lateral separation while permitting relative movement in the direction of elongation of said holes, compression springs, and means for retaining said compression springs between said side frames to urge them apart in the direction of the elongation of said elongated holes.

3. A model railway passenger car truck assembly including the combination of an equalizer having journal box openings, a side frame having vertically elongated journal box apertures, said openings and apertures being adapted for mutual registration when said equalizer and frame are cooperatively positioned parallel each other, journal boxes adapted for insertion in said openings and engagement with said equalizer and to extend therefrom inwardly through said side frame apertures, and fastenings for the inner ends of said journal boxes on the inside of said side frame to prevent their withdrawal from said apertures, whereby said journals may function to interfasten said equalizer and frame against lateral separation while permitting vertical movement of said equalizer relative to said side frame for distances limited by the lengths of said apertures, said journal boxes having inwardly directed axle openings.
